MECHANICAL BOX OPENER

Joseph K. C. Fat, Honolulu, Territory of Hawaii,
assignor of one-half to Edwin Starr, San Francisco, Calif.

Application July 17, 1951, Serial No. 237,197

5 Claims. (Cl. 145—21)

1

The present invention relates to improvements in mechanical tools and more particularly to a mechanical opener which is adapted for use in opening crates, boxes and the like.

An object of the present invention is to provide a mechanical opener which is comprised of a pair of relatively movable jaw elements, means being provided for effecting relative movement between the jaw elements and means for selectively preventing relative movement between the jaw elements.

Another object of the present invention is to provide means whereby relative movement of the jaw elements can be effected by pivoting movement of a handle, effecting rotation of a pinion in a first direction, rack teeth being provided on at least one of the jaw elements for cooperation with the pinion whereby pivoting movement of the handle effects movement of the one jaw element relative to the casing slidably supporting the same.

Various other objects and advantages will become apparent from the detailed description to follow. The best form in which I have contemplated applying my invention is clearly illustrated in the accompanying drawings, wherein:

Figure 1 is a perspective view of the entire mechanical opener shown applied to a box which is being opened;

Figure 2 is a top plan view of the mechanical opener of Figure 1;

Figure 3 is a vertical longitudinal sectional view taken substantially along the plane of line 3—3 of Figure 2;

Figure 4 is a horizontal transverse sectional view taken substantially along the plane of line 4—4 of Figure 3;

Figure 5 is a side elevational view of the mechanical opener with parts broken away;

Figure 6 is a detail perspective view of a pair of the elements employed in the present invention;

Figure 7 is a side elevational view of the mechanical opener and to the side opposite shown in Figure 5;

Figure 8 is a vertical transverse sectional view taken substantially along the plane of line 8—8 of Figure 7; and

Figure 9 is a detail perspective view of the coacting jaw portions of the present invention.

Referring more particularly to the drawings, wherein like numerals designate like parts throughout, the numeral 10 designates generally the mechanical opener being applied to a box or crate 12 for removing the cover 14 therefrom.

2

The mechanical opener 10 is comprised of a substantially rectangular casing 16, relatively movable jaw elements 18 slidably carried within the casing 16 and actuating means 18.

5 The casing 16 includes a pair of side walls 22 and 24 joined by an end wall 26 having an open end 28, the top and bottom of the casing 16 being open at 30 and 32. The casing 16 has a pair of substantially U-shaped brackets 34 and 36 joining upper and lower portions thereof whereby the open end 28 is in the form of an elongated rectangular slot through which the jaw elements can slidably extend.

10 The casing 16 has its one end face 26 marked with a laterally extending rectangular portion 38 having a downwardly extending wall 40 perpendicularly secured thereto. A pin 42 extends through the wall 40 and has a pair of pawl elements 44 and 46 pivotally carried thereby on opposite sides of the wall 40. A pair of springs 48 engage the underside of the laterally extending wall 38 and the upper arms of the pawls 44 and 46 for downwardly urging the arms 50 and 52 on the pawls 44 and 46. The purpose of the pawl arrangement will be more fully understood hereinafter.

15 As seen best in Figures 1, 5 and 7, the casing side walls 22 and 24 have a pair of supporting ears or brackets 54 and 56 suitably secured thereto, as by weld, with the bearing portions 58 disposed in parallel relation to each other. A lug 60 is fixedly supported by the ears 58, having a lock washer 62 and nut 64 engaged on the threaded end thereof.

20 The handle means for the mechanical opener includes a first handle 66 of the pistol grip type and to which handle is fixedly secured to the casing 16 at 68. A second handle 70 is formed with a hand grip portion 72 and a bifurcated or U-shaped portion 74 which is pivotally carried by the lug 60 between the ears 58. A pinion 76 is rotatably carried by the lug 60 and is disposed between the leg portions 78 and 80 of the bifurcated portion 74.

25 As will be seen best in Figures 1, 3 and 5, the pawls 44 and 46 will have their second arms 50 and 52 engageable in the teeth of the pinion 76. The arms 50 and 52 have beveled faces 51 and 53 whereby rotation of the pinion 76 in a first direction will outwardly urge the arms 50 and 52 of the pawls, whereas rotation of the pinion 76 in an opposite direction will be prevented by the arms 50 and 52 on the pawls.

30 The means for interconnecting the pinion 76 with the handle 70 includes a substantially semi-

cylindrical shaft 82 which is best disclosed in Figures 3 and 6. The semi-cylindrical shaft 82 has a bearing portion 84 and a reduced diameter spring carrying extension 86. The semi-cylindrical shaft 82 is rotatably carried by the leg portions 78 and 80 of the bifurcated portion 74 of the handle 70, the bearing portion 84 being disposed in the leg 80 while the spring carrying extension 86 rotatably extends through an opening in the leg 78. A torsion spring 88 is engaged over the extension 86 and has one end 90 engaged through the aperture 92 in the extension 86. Opposing end 94 of the torsion spring 88 is engaged in an aperture 96 in the leg 78. The main section of the semi-circular shaft 82 is adapted to engage 10 the teeth of the pinion 76 as will be readily seen in Figure 3.

The jaw means 18 includes a first jaw element 98 and a second jaw element 100. The first jaw element 98 is of substantially rectangular cross section and is slidably disposed within the casing 16. The jaw element 98 has a laterally extending jaw 102 integrally formed therewith, the upper portion of the jaw element 98 being of reduced 20 cross sectional area at 104. The inner face 106 of the jaw element 98 is formed with rack teeth 108.

The second jaw element 100 is of substantially U-shaped form and is also slidably received within the casing 16, a second jaw 110 being integrally 30 formed therewith and extending laterally therefrom for coaction with the first jaw 102. A second jaw element 100 slidably receives the reduced cross sectional portion 104 of the first jaw element 98 and has its inner face 112 formed with rack teeth at 114. The casing 16 has a pinion 116 rotatably carried thereby and engaging the rack teeth 108 and 114 of the two jaw elements 35 whereby movement of one of the jaw elements will effect relatively opposite movement of the other jaw element.

Looking now at Figures 1, 7 and 8, it will be seen that the bracket 54 is formed with an elongated slot 118 exposing a portion of the second jaw element 100 to which a stop screw 120 is adjustably secured in a preselected one of the threaded bores 122 or 124. The head of the stop screw 120 is engageable within the slot 118 for limited movement relative to the casing.

The jaw 110 is formed with a tapered outer end 126 bifurcated at 128 and has a recess formed therein. The jaw 112 is similar to the jaw 110, having a tapered portion 130 and bifurcated portion 132. The jaw 112 is also formed with a cutter insert 134 which is engageable in the recess of the jaw 110, whereby the jaws can be employed for effecting a cutting operation when desired.

In view of the foregoing description of the structure of mechanical opener of the present invention, it is believed that one skilled in the art will readily understand the manner in which the device can be employed for opening boxes, crates and the like.

When it is desired to open a box or crate such as 12, the tapered ends of the jaws 102 and 110 are engaged between the main portion of the box 12 and the cover 14. The handle 70 is pivoted in a pumping fashion. The semi-shaft 82 will engage the pinion 76 for effecting rotation thereof upon downward pivoting movement of the handle 70, upward movement of the handle 70 merely being accompanied by the riding of the semi-circular shaft 82 over the teeth of the pinion 76. The pawls 44 and 46 will prevent the pinion 76

from rotating in a reverse direction. Inasmuch as the pinion 76 is engaged with the rack teeth 77 formed on the second jaw element 100, the second jaw element 100 will be upwardly moved to the dotted line position 101. The pinion 116 will effect relatively opposite movement of the first jaw element 98 to the dotted line position 99. It will thus be seen that the cover 14 will be separated from the main portion of the box.

When it is desired to release the jaws for movement toward each other, the pawls 44 and 46 are pressed in opposition to the springs 48.

In view of the foregoing, it is believed that a device has been provided which will accomplish all of the objects hereinabove set forth. Obviously, other operating means such as electrical, hydraulic or pneumatic means could be employed for operating the opener if desired.

Having described the invention, what is claimed as new is:

1. A mechanical opener comprising a casing having a first jaw element laterally extending therefrom and in slidable relation thereto, a second jaw element slidably carried by said casing for movement relative to said first jaw element, actuating means for effecting relative movement between said jaw elements, and stop means for selectively maintaining said jaws from movement toward each other, said actuating means including a handle having a substantially U-shaped portion pivotally carried by said casing, a pinion rotatably carried by said casing and between the legs of said handle, ratchet means selectively interconnecting said handle with said pinion whereby pivoting movement of said handle in one direction effects rotation of said pinion in a first direction, one of said jaw elements having rack teeth formed thereon and engaged with said pinion whereby pivoting movement of said handle can effect relative movement between said jaw elements, the juxtaposed and opposing face portions of said jaw elements having rack teeth formed thereon, a second pinion rotatably supported by said casing and between said juxtaposed face portions and engaging said rack teeth, movement of said second jaw element effecting relatively opposite movement of said first jaw element.

2. A mechanical opener comprising a casing having a first jaw element laterally extending therefrom and in slidable relation thereto, a second jaw element slidably carried by said casing for movement relative to said first jaw element, actuating means for effecting relative movement between said jaw elements, and stop means for selectively maintaining said jaws from movement toward each other, said actuating means including a handle having a substantially U-shaped portion pivotally carried by said casing, a pinion rotatably carried by said casing and between the legs of said handle, ratchet means selectively interconnecting said handle with said pinion whereby pivoting movement of said handle in one direction effects rotation of said pinion in a first direction, one of said jaw elements having rack teeth formed thereon and engaged with said pinion whereby pivoting movement of said handle can effect relative movement between said jaw elements, the juxtaposed and opposing face portions of said jaw elements having rack teeth formed thereon, a second pinion rotatably supported by said casing and between said juxtaposed face portions and engaging said rack teeth, movement of said second jaw element effecting relatively opposite movement of said first jaw element.

movement of said first jaw element, said stop means including a pawl pivotally carried by said casing and engageable with said pinion for preventing rotation in a second direction, and a spring urging said pawl into engagement with said pinion.

3. A mechanical opener having first and second jaw elements slidably disposed therein, portions of said jaw elements being parallel to and spaced from one another and having facing rack teeth thereon, a pinion rotatably carried by said casing interengaging said rack teeth for slidably moving said jaw elements with respect to one another, actuating means for said jaw elements, said actuating means comprising a handle having a U-shaped end pivotally secured to said casing, a second pinion rotatably carried by said casing exteriorly thereof and being disposed within said U-shaped handle end, one of said jaw elements having a second set of rack teeth thereon engaged with said second pinion, and ratchet means on said handle for moving said second pinion in one direction thereby oppositely sliding said jaw elements within said casing, said jaw elements including laterally extending jaws projecting exteriorly of said casing in alignment with one another and movable toward and away from one another in response to movement of the handle.

4. A mechanical opener having first and second jaw elements slidably disposed therein, portions of said jaw elements being parallel to and spaced from one another and having facing rack teeth thereon, a pinion rotatably carried by said casing interengaging said rack teeth for slidably moving said jaw elements with respect to one another, actuating means for said jaw elements, said actuating means comprising a handle

having a U-shaped end pivotally secured to said casing, a second pinion rotatably carried by said casing exteriorly thereof and being disposed within said U-shaped handle end, one of said jaw elements having a second set of rack teeth thereon engaged with said second pinion, and ratchet means on said handle for moving said second pinion in one direction thereby oppositely sliding said jaw elements within said casing, said jaw elements including laterally extending jaws projecting exteriorly of said casing in alignment with one another and movable toward and away from one another in response to movement of the handle, said first jaw element being of inverted U-shaped configuration, one of the legs of said U-shaped jaw element having the second set of rack teeth thereon, and the other leg terminating in one of the laterally extending jaws, said second jaw element being disposed between the legs of said first jaw element.

5. The combination of claim 4, said second jaw element comprising an elongated bar having an upper portion of reduced cross-section providing a shoulder between the upper and lower portions thereof, the other of said laterally extending jaws projecting from said second jaw element adjacent said shoulder and underlying said one jaw, said other leg of said first jaw element being reciprocally slidable on said upper portion of said second jaw element.

JOSEPH K. C. FAT.
